UNITED STATES PATENT OFFICE

JOSEPH SOBCZAK, OF DULUTH, MINNESOTA, ASSIGNOR OF ONE-HALF TO HENRY LABELLE, OF DULUTH, MINNESOTA.

FARE BOX

Application filed April 8, 1929. Serial No. 353,307.

This invention relates to fare boxes such as used in street cars, busses, or the like, for receiving, collecting, or sorting the various coins or tokens received as fare, and has 5 special reference to a novel form of device for separating the tokens from the rest of the coins when delivered from the coin carrying wheel; said tokens being retained within a suitable receptacle or chamber beneath the 10 wheel and separated from the other coins which are in a chamber by themselves.

The principal object is to relieve the operator or conductor of the necessity of separating the tokens from the other coins immediately upon taking same from the fare box; this being particularly applicable to what is now commonly known as one man operated cars, that is to say where the operator acts both as the motorman and conductor.

20 Among the fare boxes commonly used are those having a main body portion in which the sorting for counting purposes of the coins takes place, and in which the coin receiving wheel is disposed at an angle above the mechanism, such angle usually being approximately 45°, and the wheel being covered by what is known as the die cast hopper. Above the main body portion of such boxes is usually an upright extension having glass sides 25 through which the coins may be seen as put into the box before dumping onto the wheel through the hopper. Beneath the main body portion is a compartment for the reception of all coins after delivery from the wheel and which are usually removed from a single compartment by the operator and subsequently 30 separated manually which becomes an objectionable source of labor on the part of the operator as above stated.

40 Other minor objects and advantages of the invention will appear in the following description thereof.

Referring now to the accompanying drawings, forming part of this application, and wherein like reference characters indicate like parts:

45 Figure 1 is a perspective view of a common fare box, of the type to which my invention 50 is applied, and illustrated as having the

wheel receiving and sorting mechanism removed previously therefrom and showing my preferred division of compartments beneath the removable mechanism of the box.

Figure 2 is a vertical section on the line 55 2—2, Figure 3;

Figure 3 is an enlarged top plan view of what is known as the die cast hopper and cover of the coin carrying wheel of such fare boxes as previously described, with the upper- 60 most coin passage cover removed,

Figure 4 is an elevation looking into the coin delivery channels from the discharge end thereof or side of the wheel cover, the cover of the token channel being shown in 65 section.

Figure 5 is a full sized side elevation of the removable coin sorting unit showing the die cast hopper in section and the inclined coin receiving wheel therebeneath in elevation. 70

1 represents the hopper cover which surrounds the coin carrying wheel 2, this cover having the hopper-like bulge portion 3 with the opening 4 in the oblique face thereof through which the coins fall when dumped from the hopper portion 50 of the box onto the wheel, the latter being disposed, as before stated, at substantially 45°. This wheel as is well known is rotated manually as by 75 a suitable crank 51, (and gear mechanism illustrated at 55) protruding from one side of the box and gearing and is designed to discharge the coins into the compartments below the wheel, after first being elevated thereby and when thus carried the coins and tokens 80 are separated by mechanism operated in conjunction with the wheel. 85

This mechanism includes in the box here illustrated, six pairs of coin gathering elements or catchers, spaced about the upper 90 circumferential face of the wheel 2, each pair including the protruding stops 52 and 53. When each pair of such stops traverse the pocket-like spaces 54 in the die cast hopper adjacent the lower edge of the wheel 2 they 95 will gather or become engaged by a coin lying thereagainst and carry it about on the wheel. Each pair of stops about the wheel being spaced for certain sized coins will gather or catch a coin or token only of the 100

proper size, thus certain of the stops gather tokens, certain others, dimes, others, nickels, and so on.

In the box here illustrated, the wheel 2 has two only of the token catchers, together with four other coin catchers; these catchers being of no concern in the present invention and forming no part thereof except as to the mechanism in connection with the pickers for separating the tokens from the other coins and causing them to traverse different discharge channels from the wheel 2.

In delivery from the wheel 2, the coins are taken therefrom by what is known as the coin picker, the forward end of which is illustrated at 5 in the drawings and is guided as by the groove 6 in the wheel and is inclined away from the wheel, delivering all of the coins and tokens through the passageway indicated at 7.

Such wheel covers 1 are also provided with a second or lower passageway indicated at 8, it being more tortuous than the upper passage, but delivering at one side thereof as at 9, while the delivery of the other passageway is indicated at 10, or if not so found must be provided for the operation of my present invention. The coin receiving ends or mouths of the passageways or channels 7 and 8 are one above the other approximately opposite the innermost terminus of the opening 4 on the cover, and the terminus of the opening 4 is formed by the wall 11 which extends inwardly from the opening forming the side wall of the hopper-like elevation 3. Upon this wall and integral therewith is formed an upright bearing member 12 adjacent the inner side of the channels, as opposite the side of such wall the channels occur one above the other and separated by the covering member 13 of the channel 8, said covering member extending across beneath the channel 7 and forming the bottom thereof, as at 14. Upon the outermost side of the channels and directly opposite the bearing member 12 is a similarly shaped upright bearing member 15, and transverse the upper end of these bearing members is normally carried the shaft or spindle 16. The covering member 50 for the passageway or channel 7 is illustrated in dotted lines at 17, is attached at one end as by the screws 18' to the side walls of the mouth of said channel passes arcuately up over the passageway, thence underneath the rod 16 and in the structure as commonly found downwardly to the upper wall 18 of the hopper cover, where it is attached by screws indicated at 19.

This entire mechanism thus far described is as above stated, found in some types of fare boxes, and forms no part of my present invention, except as cooperative therewith.

My invention resides in the bending up of the extreme forward end of the cover 17 to a position as shown at 20 in Figure 3 of the

drawings to permit of the installation of the novel mechanism forming the invention. A shaft 21 is installed beneath the shaft 16 and just opposite the innermost edge of the cover plate 13 within the uprights 12 and 15. Upon this shaft is mounted the slightly upwardly arched coin ramp 22 by its having downwardly bent lugs 23 upon either side thereof adjacent its discharge end and through which the shaft 21 is mounted, thus forming a pivotal support for the ramp, the forward end of which normally rests within a suitable transverse slight depression on the ramp 24 beneath same, and which latter ramp extends considerably beyond the ramp 22, terminating in the forward pallet-shaped end 5, previously described. This latter ramp or coin picker is attached as by the screws 25 to the notched extension of the floor 26 of the lowermost coin passageway or channel 8, and which floor spaced some distance above the coin carrying wheel 2, and maintains a permanent position as shown in respect to the coin carrying wheel so that all coins are lifted thereby onto at least the forward end thereof.

Just forwardly of the shaft 21 and formed integral with the ramp 22, are upwardly extending side members 27 carrying the diagonally disposed transverse wall 28 therebetween, said wall 28 having an elongated hole 29 centrally thereof, this wall being spaced considerably above the surface of the ramp, in fact occupies approximately the upper half of the uprights 27.

Through the hole 29 protrudes the angularly disposed free terminus 30 of the ramp operating arm 31 which is fixed for example as by a cotter to the upright shaft 32 mounted within the projecting lug 33 on the edge of the hopper cover. This shaft 32 extends downwardly through the lug 33 and upon the lower end thereof has fixed in a like manner to the arm 31 the arm 34 which is arcuate in form and lies normally close against the lower edge of the hopper cover, except adjacent its free end where the lower edge of the hopper is cutaway and permits the extreme angularly disposed free end 35 to assume a position beneath and close to the lower circumferential surface of the coin carrying wheel or disc 2.

Now for cooperation with this free end of the arm 34 I have fixed to the lower circumferential edge of the disc 2 arcuately shaped plates 36 at intervals about the disc and in this instance I have employed only two, for on the coin carrying disc here illustrated there are but two pair of token catching elements, and these plates are so positioned in advance of the token catching elements that they will engage the free end 35 of the arm 34 and operate same to rotate the shaft 32 thus swinging the arm 31 in a like manner and in the same direction which will tip up the ramp 130

22 and allow the token then just falling from the wheel to pass intermediate of the ramps 22 and 24 and out through the token channel 8 to its respective compartment below the wheel 5 or disc. But immediately upon the passage of the token between the ramps the respective plate 36 will have passed the free end 35 of the arm 34 and permit of the return of the arms 31 and 34 to their normal position which 10 is maintained by the contractile helical spring 37, one end of which is attached to the arm 31 and the other end hooked into the end wall 11 of the opening 4 in the hopper cover, thus closing the passage between the forward ends 15 of the ramps and compelling all other coins as they are carried about on the wheel by their respective catching element to pass over the ramp 22 through the passage 7 and discharge into their respective receptacle, below the 20 wheel operating mechanism. This receptacle or chamber for the promiscuous coins is illustrated at 38 and is preferably considerably larger than the chamber or receptacle 39 alongside of same for the reception of the 25 tokens only; this being an obvious convenience to the operator in removing the coins and tokens from the box.

It will be noted that the entrances to the compartments 38 and 39 are illustrated at 30 40 and 41 respectively so as to register with the discharges 9 and 10 of the coin passageways previously described.

Having thus described my invention, what I claim and desire to secure by Letters Patent, is:

1. In combination, a fare box coin and token carrying and selecting wheel, and two intermittently cooperating ramps for conveying the coins and tokens to separate 40 depositories.

2. In a fare box having a coin and token carrying and selecting wheel and a coin and token picking ramp for said wheel, a token picking ramp above said first mentioned ramp 45 and means operable by the wheel for causing the token picking ramp to intermittently function at predetermined times.

3. In combination a fare box coin and token carrying selecting wheel and a fixed ramp for 50 conveying the coins and tokens from said wheel towards a single passageway, and an intermittently operable ramp for cooperative engagement with the first mentioned ramp whereby all tokens are directed to a 55 separate passageway.

In testimony whereof I affix my signature.
JOSEPH SOBCZAK.
